UNITED STATES PATENT OFFICE.

EDWARD S. MARSHALL, OF ST. LOUIS, MISSOURI, ASSIGNOR TO THE MISSOURI RAILWAY EQUIPMENT COMPANY, OF SAME PLACE.

DESIGN FOR A JOURNAL-BOX LID.

SPECIFICATION forming part of Design No. 26,469, dated December 29, 1896.

Application filed November 23, 1896. Serial No. 613,204. Term of patent 14 years.

To all whom it may concern:

Be it known that I, EDWARD S. MARSHALL, a citizen of the United States, residing at the city of St. Louis, State of Missouri, have invented a certain new and original Design for Lids for Journal-Boxes, of which the following is a full, clear, and exact description, reference being had to the accompanying drawings, forming a part of this specification, 30 wherein—

Figure 1 is a top plan view. Fig. 2 is a side elevational view. Fig. 3 is a bottom plan view. Fig. 4 is a sectional view.

This invention relates to a new and original design for lids for journal-boxes; and it consists in the shape, configuration, and ornamentation illustrated in the drawings and hereinafter fully set forth.

In the drawings, A indicates a lid. At the rear and about midway between the side edges thereof rises a hollow extension B. The side walls of this extension are straight and substantially perpendicular, while its rear wall rises at an incline nearly perpendicular and joins the top wall at an angle thereto, said top wall gradually falling at an incline and terminating at or about the center of the lid. The edges of the extension B are rounded, as shown.

The rear edge of the flat portion of the lid 35 is slightly inclined downward, as shown. Integral with this inclined portion and extending on each side of the base of the extension B and integral therewith are two hollow cylindrical projections C.

From the side and front edges of the lid depends a flange D, while at the front edge and on a plane with the top of the lid is a projection E, the edge of which is curved, as shown.

F indicates a bail-like extension projecting 40 from the lower face of the lid, and G a small stud or projection which is situated between said extension F and terminating point of the top wall of the hollow extension B.

The upper face of the lid is ornamented by 45 a beading H, substantially as shown in the drawings.

What I claim is—

The design for a lid for journal-boxes, substantially as herein shown and described. 50

In testimony whereof I hereunto affix my signature, in presence of two witnesses, this 18th day of November, 1896.

EDWARD S. MARSHALL.
